UNITED STATES PATENT OFFICE.

JOHN GREEN, OF ST. LOUIS, MISSOURI, ASSIGNOR TO J. S. ANDREWS & COMPANY, OF NEW YORK, N. Y., A CORPORATION OF NEW YORK.

CAR-TRUCK.

No. 838,320.

Specification of Letters Patent.

Patented Dec. 11, 1906.

Application filed September 12, 1906. Serial No. 334,264.

To all whom it may concern:

Be it known that I, JOHN GREEN, a citizen of the United States, and a resident of the city of St. Louis and State of Missouri, have 5 invented a new and useful Improvement in Car-Trucks, of which the following is a specification.

My invention relates to car-trucks, and has for its principal object to improve the 10 means for hanging the brake.

It consists in the parts and in the arrangements and combinations of parts hereinafter described and claimed.

In the accompanying drawings, which 15 form part of this specification, and wherein like symbols refer to like parts wherever they occur, Figure 1 is a view of a side frame embodying my invention, partly in elevation and partly in longitudinal vertical section. 20 Fig. 2 is a vertical cross-section on the line 2 2 of Fig. 1 of a truck side frame embodying my invention with the brake-hanger shown in position. Fig. 3 is a cross-sectional detail of the brake-hanger hook, showing its relation to the side frame prior to being upset 25 therein, and Fig. 4 is a detail end view of the boss in which the brake-hanger hook is mounted.

In ordinary car-building practice the 30 distance from the side frame to the point where the brakes are hung is approximately nine inches. Heretofore cast-steel side frames have been formed with the brake-hanger hook integral therewith; but on account of 35 the necessary length of such hook it was liable to be cast defectively and was also liable to break off in practice, in which case the whole side frame had to be discarded.

In the present invention the side frame 1, 40 which may be of any suitable construction, has bosses 2 formed on its outer face, and through these bosses extend horizontal holes. The body portion of the holes is preferably circular, while the outer portion thereof—that is, the portion in the bosses—flares outwardly and is of polygonal section. 45 Mounted in each of the holes on the side frame is a brake-hanger hook. The brake-hanger hook comprises a body portion 3 of proper size and length to extend through the

hole in which it is mounted and a portion 4, which projects inwardly from the side frame and terminates in an upwardly-extending hook 5. This brake-hanger hook is provided with a shoulder 6, adapted to abut 55 against the inner face of the side frame. The outer end of the brake-hanger hook is of proper length to project outwardly beyond the boss on the outer face of the side frame. In practice the body portion 3 of the brake- 6c hanger hook is heated and then set into the hole in the side of the frame from the inner side and properly positioned. While its projecting end portion is still hot, it is swaged or upset against the flaring pyramidal inner 65 wall of the boss, whereby it is firmly locked against rotation, as well as against all other motions relative to the side frame.

The advantages of the foregoing construction are obvious. In the first place it eliminates one of the difficulties of casting the side frame. It permits the brake-hanger hook to be made of the shape and material most suitable for its purpose—for instance, wrought-steel—whereas heretofore said hook 75 has been made of cast-steel and its form has been limited by the requirements under which it was produced. In case of breakage the hanger-hook can be cut out from the side frame and replaced with another brake- 80 hanger hook without having to discard the side frame or even to remove it from the truck.

Obviously my device admits of considerable modification within the scope of my invention, and therefore I do not wish to be limited to the specific construction shown and described.

What I claim is—

1. A car-truck comprising a side frame 90 having a horizontal hole therein and a brake-hanger hook mounted in said hole.
2. A car-truck comprising a side frame having an outwardly-flaring horizontal hole 95 therein and a brake-hanger mounted in said hole.
3. A car-truck comprising a side frame having a horizontal hole whose outer portion flares pyramidal and a brake-hanger hook comprising a body portion upset in said py- 100

ramidal portion and a hook portion projecting from the inner face of said side frame.

4. A car-truck comprising a cast-metal side frame having bosses on its outer face and outwardly-flaring holes extending horizontally through it, and brake-hanger hooks each having a body portion upset in the flar-

ing portion of a hole and an upturned portion projecting from the inner face of said frame.

St. Louis, Missouri, September 7, 1906.

JOHN GREEN.
